JAMES MULARKEY, OF KANSAS CITY, MISSOURI, ASSIGNEE OF ONE-HALF TO JAMES P. SPRAGUE, OF KANSAS CITY, MISSOURI.

BUILDING-PARTITION.

1,110,707.

Specification of Letters Patent. Patented Sept. 15, 1914.

Application filed December 9, 1913. Serial No. 895,617.

To all whom it may concern:

Be it known that I, JAMES MULARKEY, a citizen of the United States, residing at Kansas City, in the county of Jackson and State of Missouri, have invented certain new and useful Improvements in Building-Partitions; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to building partitions, and more particularly to a partition comprising spaced studs having plaster board applied and attached to its opposite vertical edges; the principal object of the 20 present invention being to provide simple and convenient means for attaching the plaster board to the studding.

In accomplishing this object I have provided improved details of structure, the preferred form of which is illustrated in the 25 accompanying drawings, wherein—

Figure I is a perspective view of a partition constructed according to my invention. Fig. II is a horizontal section of the same. 30 Fig. III is a side elevation of a portion of one of the studs with fastener members mounted thereon. Fig. IV is an enlarged detail perspective view of one of the fastening members.

35 Referring more in detail to the parts:— 1 designates the floor and 2 the ceiling in a building that is divided into separate rooms or compartments by my improved partition.

40 Extending along the partition lines and fixed to the floor and ceiling in vertical alinement are upper and lower channel irons 3—4, and seated in said channel irons, and extending vertically therebetween, are I-beams 5, each formed of two channel irons arranged back to back, and permanently connected by rivets or the like 7.

Located between the channel irons of the I-beams are fasteners 8, each preferably comprising a single piece of sheet metal having its opposite ends projecting from opposite sides of the I-beam and having its body portion fixed in the I-beam by the rivet 7 which anchors the I-beams.

One end of each of the fastening members 8 is preferably provided with a single point 10 and the opposite end with a pair of spaced points 11, and the arrangement of the fasteners in each studding is preferably such that the single points alternate with the double points on the same side of the studding for the purpose presently described.

It is a well known fact that the plaster board ordinarily used for partition work is substantially twice the length of the space 65 between the studding, so that the center of each board overlies one of the partition studs, while its ends overlie portion of alternate studs.

In order to fasten the board permanently 70 to the studding, I have provided the fasteners 8, heretofore described, and provide the double pointed ends in order that the ends of adjacent plaster boards may abut against opposite sides of the points 11 so that one 75 of the points may fold over one of the boards and the opposite point fold in the opposite direction over the other board to hold both boards in place.

With the alternate arrangement of the 80 single and double points on the same side of the partition, the double points may be folded as described, so that both of the spacer boards may be held by the same fastener and the single points may alternate 85 over the two boards, to assist the double points in holding the boards in place.

In erecting a partition with my improvements the studding is erected in the usual manner and the plaster board applied by 90 placing each board across one of the studs, so that its ends may lie against the alternate studs and against the sides of the projecting points of the fasteners on such alternate studs. The plaster board is then 95 forced against the projecting points of the fastening members on the middle stud until the points penetrate the board to enable the latter to seat flatly against the studding. The points of the fasteners on the intermediate stud are then folded over the board and the single and double fasteners on the alternate studs folded thereover, as illustrated in the drawing, to permanently attach the board to the studding.

100 It is apparent that after the board has been attached to the studding, plaster may be applied thereto to complete the partition;

the joints of the boards at opposite sides of the partition being preferably broken in order to form a more rigid wall.

Having thus described my invention, what I claim as new therein, and desire to secure by Letters-Patent, is—

A partition comprising studding having fastening members permanently secured thereto, each fastening member being formed from a single piece of sheet metal, having a

single point at one end and a double point at the opposite end, with the single and double points alternating at the same side of the partition.

In testimony whereof I affix my signature to
in presence of two witnesses.

JAMES MULARKEY.
